INVENTOR.

Emil M. Heineke

UNITED STATES PATENT OFFICE.

EMIL M. HEINEKE, OF SPRINGFIELD, ILLINOIS.

CAR-CHECK HOLDER.

1,397,889.

Specification of Letters Patent.

Patented Nov. 22, 1921.

Application filed December 31, 1920. Serial No. 434,218.

To all whom it may concern:

Be it known that I, EMIL M. HEINEKE, residing at Springfield, in the county of Sangamon and State of Illinois, have invented new and useful Improvements in Car-Check Holders, of which the following is a specification.

My invention relates particularly to devices for holding car checks of metallic or other compositions commonly used for street railway fares.

An object of my invention is to provide a new and improved car check holder which is comfortable in the pocket, convenient to use and inexpensive.

A further object of my invention is to provide a quick and easy means of quickly discharging the car check into the change box with the use of only one hand necessary, since it is obvious that a passenger often has one arm loaded with merchandise and necessarily finds it inconvenient to use both hands in preparing to pay his car fare.

A further object of my invention is to provide a springy actuated arm adapted to project successive coins outwardly through a slot in the container and in conjunction with said lever to provide a locking device adapted to hold the lever optionally in its latched position.

The preferred embodiment of my invention is hereinafter described and illustrated in accompanying drawings.

Reference is to be had to the accompanying drawings forming a part of this specification, in which similar letters of reference indicate corresponding parts in all the figures.

In the drawings, Figure 1 is a longitudinal section of the car check holder of my invention, taken on the axis thereof;

Fig. 2 is a side elevation of the metallic cylindrical casing 1, to be used as a magazine for containing car checks.

Fig. 3 is a side elevation of the combination of a base cap 2, feed spring 4 and plunger 3.

Fig. 4 is a perspective of the thumb latch button.

Fig. 5 is a perspective of the resilient strip 24, in Fig. 1.

Fig. 6 is a perspective of the slotted metallic plunger.

Fig. 7 is a plan or top view of the car check holder.

It will be observed that the nature of my invention is fairly well illustrated in Fig. 1.

The metallic cylindrical casing (Fig. 2) is adapted to be used as a magazine in which to hold the car checks, said casing having one end 21 open to admit the car checks 13 and coil spring plunger 3. Near the opposite end of said casing is a discharge slot 20 cut horizontally with respect to the length thereof, constituting an outlet opening for the discharge of car checks. Opposite said discharge slot 20 is a slot 23 cut to accommodate the movement of the plunger Fig. 6.

On the outside and near the respective ends of said casing are engaging slots 5 and 7. These slots are pressed out of the cylindrical casing 1. At 5 the resilient strip 24 is securely soldered to the casing, and at 7 the thumb latch button (Fig. 4) is detachably securable thereto.

The compression spiral spring plunger and base cap (Fig. 3) is a combination which is adapted to hold the car checks compactly within the casing.

The thumb latch button (Fig. 4) is adapted to be used as a press button when discharging car checks, and as an engaging latch with which to hold resilient strip 24 and slotted metallic plunger Fig. 6 detachably engaged with cylindrical casing Fig. 2 when not in use.

Fig. 5 is a perspective of the resilient strip 24 having therein a short longitudinal slot 18 within which thumb latch button Fig. 4 operates as described, and on which is securely attached by solder parallel spring wires 17 adapted to exert a constant tension against bar 16 on the thumb latch button Fig. 4 to keep said button where it is optionally placed, whether in an engaged or disengaged position.

This resilient strip is securely attached at end 6 to the cylindrical casing at 5 and the opposite end of said resilient strip is looped to form a part of a hinged connection with the slotted plunger Fig. 6.

A hinge pin 15 is used in forming the hinged connection between said resilient strip and said slotted plunger.

The slotted metallic plunger Fig. 6 has a longitudinal slot therein which is adapted to be used for holding the plunger in proper alinement in action and having the contact end thereof 11 closed to enable the plunger

to come in contact with pin 22, when being retracted. Said pin is soldered to casing 1 across slot 23 to keep said plunger from slipping out of said casing when being retracted.

5 The opposite end of said plunger at 12 is looped to form a part of the hinged connection between the plunger and resilient strip. This plunger is designed to be approximately the same thickness as the coins commonly used and means are provided in the operation of the discharge plunger whereby said plunger is detachably secured within the discharge slot passage when not in use, thereby holding all remaining coins securely and compactly within the magazine until it is desired to discharge them successively.

Fig. 7 is a plan or top view of the car check holder of my invention shown as it would look with a car check partially discharged therefrom.

When the operator desires to use the car check holder of my invention, he releases the bottom cap 2 (Fig. 2) and withdraws the spring 4 and plunger 3 from the coin chamber by pulling on the base cap 2; then the car checks are put in the magazine, after which the feed spring (Fig. 3) is reinserted and secured in its operative position.

When it is desired to discharge a car check therefrom, the operator releases with his thumb the thumb latch 19 from its engaging slot 7, thus permitting the resilient strip 24 to normally retract, effecting an automatic retraction of the discharge plunger Fig. 6, to which said resilient strip 24 is hingedly connected at 10. The operator may now effect a complete discharge of the car check by exerting a slight pressure of the thumb on button 14, whereby the slotted metallic plunger Fig. 6 is forced to completely discharge the coin 13 from the slot 20 in cylindrical casing 1.

It is obvious that the details of construction may be made in many ways, and yet stay within the spirit and scope of the appended claims.

Having thus described the nature of my invention, what I claim as new and useful and of my own invention, and desire to secure by Letters Patent is:

1. In a car check holder of the character described, having a slotted metallic discharge plunger, a metallic cylindrical casing and a thumb latch button, a resilient strip mounted 55 on the outside and near the open end of a metallic cylindrical casing, said resilient strip being adapted to automatically retract said discharge plunger; means connecting said resilient strip with said discharge plunger and means for detachably engaging said resilient strip with said casing when not in use; said resilient strip having a short longitudinal slot therein and parallel wire springs securely attached thereto near the

operative end thereof and having its slotted end turned to form a hinge loop therein, as and for the purpose set forth.

2. In a car check holder of the character described, having a stop device in conjunction with a transversely slotted metallic cylindrical casing, a longitudinally slotted metallic plunger adapted to be used as a discharge plunger for the discharge of car checks, having one end thereof looped to form a hinge section and the other end squared off to neatly close the longitudinal slot therein; means provided in a stop device secured transversely across the slot through which said discharge plunger normally slides in said casing, said stop device adapted to arrest the movement of said plunger at predetermined limits, as and for the purpose set forth.

3. In a car check holder of the character described, having a resilient strip and a slotted metallic plunger hingedly connected and a metallic cylindrical casing, a combination comprising a wire soldered transversely across a guide slot in a cylindrical casing, forming a guide for said discharge plunger and a stop device in conjunction with said guide slot adapted to hold said discharge plunger within predetermined limits, substantially as set forth.

4. In a car check holder of the character described, having a resilient strip with a short longitudinal slot therein and parallel wire springs soldered thereon, a device comprising in combination, a sliding thumb latch button adapted to be operated within said slot of said resilient strip; means provided in a pin securely attached to said sliding latch button to coördinate with said parallel wire springs in holding said sliding latch button substantially where located when thumb control is released, as and for the purpose set forth.

5. In a car check holder of the character described, having a metallic cylindrical casing, with an engaging slot pressed out of the slide thereof, a combination comprising a resilient strip and a slotted metallic plunger having a hinge connection and a sliding thumb latch button slidable within the slot in said resilient strip and detachably engageable with a catch on the outer side of said cylindrical casing, adapted to optionally render the complete discharge of car checks successively, all substantially as and for the purpose set forth.

In witness whereof I have hereunto set my hand this 28th day of December, A. D. 1920.

EMIL M. HEINEKE.
